HORN SUPPORT

Application filed December 18, 1929. Serial No. 415,257.

This invention relates to horn supports and more particularly to horn towers for use in sound picture installations.

The primary object of the invention is to provide an efficient support of simple construction for adjustably positioning a horn.

In accordance with one embodiment, the invention contemplates the provision of a movable tower having three movable platforms supported one on top of the other, the lower two platforms providing straight-line movement transversely of each other and the uppermost platform being rotatable. The horn which is connected to sound picture equipment is adjustably suspended from the uppermost platform on the tower whereby the position of the horn may be adjusted to obtain the best acoustical effect.

Other objects and advantages of the invention will become apparent from the following detailed description when considered in conjunction with the accompanying drawings, wherein

Fig. 1 is a fragmentary front elevational view of a horn tower support embodying the invention;

Fig. 2 is an enlarged fragmentary plan view thereof;

Fig. 3 is an enlarged fragmentary side elevational view of the horn support on the tower;

Fig. 4 is a plan view of a modified horn support in which only two movable platforms are used in the tower, and

Fig. 5 is a partial side elevational view of the modified horn support, shown in Fig. 4.

Referring now to the drawings wherein like reference numerals designate the same parts throughout the several views, four uprights or standards 10-10 and a plurality of cross pieces 11-11 are assembled to form the frame of a rectangular tower 12, which is mounted on casters 13-13 to permit it to be moved readily to different locations. As shown in Figs. 1 to 3, inclusive, the upper front and rear cross pieces 11 are of L-shaped cross section to form guide members which provide a runway for rollers 15-15 supporting a platform 16 (hereinafter called the lower platform) which has L-shaped guide

members 17-17 secured thereon for guiding and supporting rollers 18-18 of an intermediate or middle platform 19. This latter platform carries on its upper surface a top platform or frame 20 which is rotatably supported by three rollers 21, 22, and 23 for expediting the movement thereof.

The frame or platform 20 includes two arms 30-31, from which the front end of a sound picture horn 32 is suspended by chains or ropes 33-33 and an arm 34 is positioned at right angles to the arms 30-31 and carries a swivel pulley 35 (Fig. 3) over which a chain or rope 36 is passed for adjustably supporting the rear end of the horn in a manner analogous to that clearly shown in Fig. 5. Slidably positioned in a slot 37 of the arm 34 are two locking members 38-39, each having a depending hook portion 40 projecting through a rectangular opening 45 of the middle platform 19 and adapted to engage and clamp the inner edges thereof when nuts 46-46 threaded on the upper ends of the members are rotated clockwise. The lower end of a vertical stud 47 is rigidly fastened to a pair of bars 48-48 secured to the inner side of the platform 19 and the upper portion of the stud extends through an aperture in a plate 25 (Figs. 2 and 3) fastened to the arm 34 so that the top platform 20 is rotatable about the stud. The locking members 38-39 prevent the top platform 20 from being moved off of the middle platform. Likewise, the middle platform is equipped with two locking members 49-49 which engage the underside of the lower platform to retain the middle platform 19 in a predetermined position with respect to the lower platform 16. The lower platform is also provided with locking members 58-58 (Fig. 3) which are adapted to grip the underside of the upper cross pieces 11 of the tower and the upper ends of these members serve as stops to prevent the middle platform 19 from being run off the ends of its guide members 17-17.

In the use of the above described equipment in sound picture productions, the horn tower is moved about the stage to a desired location adjacent the picture screen. The definite location of the horn within the tower

relative to the screen is then adjusted by manually moving the three platforms 17, 19, and 20 in the tower to desired positions and locking them in place and the horn is tilted by means of the pulley 35 and the rope 36 to thereby properly position the horn to obtain the best acoustical effect in the theater.

In another embodiment of the invention disclosed in Figures 4 and 5, the tower 12 has secured on its top two L-shaped guide members 50—50 supported by a frame member 11 and a cross piece 51. A platform 52 is movably supported on the guide members 50—50 by rollers or casters 53—53 whereby the platform can be expeditiously moved longitudinally of the tower. Bolts 54—54 secured to laterally extending portions 55—55 of the guide members 50—50 protrude upwardly through slots 56—56 in the platform 52 and have nuts 57—57 threaded thereon for clamping the platform in a predetermined position on the tower. Supported by three rollers 60—60 on top of the platform 52 is a triangular frame 61, from the base end of which a sound picture horn 62 is suspended by ropes or chains 63—63. The apex of the triangular frame has pivoted on its underside a pulley 64 over which passes a rope or chain 65 having one end fastened to the rear portion of the horn 62 and the other end secured to a tie-bar 69 forming a part of the tower. By means of the rope and the pulley the horn can be tilted at any desired angle. Secured to and forming a part of the triangular frame 61 is a plate 70 which is pivoted on an upright bolt 71 secured to the platform 52. The plate 70 also carries two bolts 72—72 which extend through arcuate guide slots 73—73 in the platform 52 and are provided with nuts 74—74 threaded thereon for locking the frame 61 on the platform.

It is believed to be obvious, without further description, that the frame 61 and the horn suspended therefrom can be rotated about the bolt 71, also that they can be moved transversely of the tower by means of the platform 52, and that by means of the rope 65 and pulley 64 the horn can be tilted relative to the tower to obtain the desired acoustical effect in any sound picture installation.

What is claimed is:

1. A horn support comprising a tower, and means mounted in the tower and movable in straight lines in different directions for supporting a horn.

2. A horn support comprising a tower, and means mounted in the tower and movable in straight lines in different directions for supporting a horn, and means for moving the horn in a vertical plane.

3. A horn support comprising a tower, a plurality of movable members operatively associated with each other and supported by the tower, one of said members supporting a horn, and means for moving said members

laterally in said tower to adjust the position of the horn.

4. A horn support comprising a tower, a plurality of movable members operatively associated with each other and supported by the tower, one of said members supporting a horn, means for moving said members laterally to a predetermined position, in said tower, and means to rotate said horn supporting member to adjust the position of the horn.

5. A horn support comprising a tower, a plurality of movable members supported by the tower and mounted one on top of the other, and means for suspending a horn from one of the members.

6. A horn support comprising a tower, means positioned in the tower for supporting a horn, and means for permitting movement of the horn supporting means in horizontal directions at right angles to each other.

7. A horn support comprising a tower, a platform mounted thereon movable transversely of the tower, means mounted on the platform and movable thereon, and a frame rotatably mounted on said means for supporting a horn.

8. A horn support comprising a tower, a platform mounted thereon movable transversely of the tower, means mounted on the platform and movable thereon, a frame rotatably mounted on said means for supporting a horn, and means for maintaining the horn in adjusted position.

9. A horn support comprising a tower, a plurality of movable members supported by the tower, means for suspending a horn from one of the members, and means for tilting the horn.

10. A horn support comprising a tower, a movable platform mounted thereon, means positioned on the platform for supporting a horn, and means for pivoting the horn support on the movable platform.

11. A horn support comprising a movable tower, a platform movably mounted thereon and supporting a horn, means for guiding the moving platform, and means for tilting the horn.

12. A horn support comprising a movable tower, a movable platform mounted thereon, guides on the tower for controlling the direction of movement of the platform, means movably mounted on the platform for supporting a horn, means for guiding the horn supporting means, means for locking the platform and horn supporting means, and means for tilting the horn.

13. A horn support comprising a tower, a lower platform movably mounted thereon, a middle platform movably mounted on the lower platform, and a movable top platform mounted on the middle platform for supporting a horn.

14. A horn support comprising a tower, a lower platform movably mounted thereon, a

middle platform movably mounted on the lower platform, a top platform rotatably mounted on the middle platform, and means for suspending a horn from the top platform.

15. A horn support comprising a tower, a lower platform movably mounted thereon, a movable upper platform mounted on the lower platform, and a rotatable means pivoted on the upper platform for carrying a horn.

16. A horn support comprising a tower, a lower platform movably mounted thereon, a middle platform movably mounted on the lower platform, a top platform rotatably mounted on the middle platform, means for suspending a horn from the top platform, and means for moving the horn relative to the platforms.

20 17. A horn support comprising a tower, a lower platform movably mounted thereon, a middle platform movably mounted on the lower platform, a top platform rotatably mounted on the middle platform, means for suspending a horn from the top platform, and means for securing the platforms in adjusted positions.

25 18. A horn support comprising a tower, a lower platform movably mounted thereon, an upper platform movably mounted on the lower platform, means for securing the lower platform to the tower and for limiting the movement of the upper platform, and means mounted on the platform for carrying a horn.

30 19. A horn support comprising a tower, anti-friction means secured to the tower for rendering it portable, a movable platform mounted on the tower, guides on the tower for controlling the movement of the platform, means movably mounted on the platform for supporting the horn, means for guiding the horn supporting means, means for securing the platform and horn supporting means in adjusted positions, and means for tilting the horn.

35 20. A horn support comprising a tower, a lower platform movably mounted thereon, means for securing the lower platform to the tower in an adjusted position, a middle platform movably mounted on the lower platform, means for securing the middle platform to the lower platform, a rotatable top platform pivotally mounted on the middle platform, means for securing the top platform to the middle platform, means for suspending a horn from the top platform, and means for tilting the horn.

40 Signed at New York, N. Y., this 26th day
of November, 1929.

DANIEL C. HICKSON.
